FEEDWATER CONTROL SYSTEM

Alfred C. Wenzel, Chicago, Ill., assignor to Republic Flow Meters Company, Chicago, Ill., a corporation of Illinois

Application November 3, 1948, Serial No. 58,062

12 Claims. (Cl. 122—451)

1

This invention relates to feedwater control systems, and more particularly to control systems for power plants having a plurality of banks or boilers to control the return flow of feedwater from separate steam consuming devices to the banks of boilers.

In power plants having a plurality of banks of boilers supplying steam to a plurality of steam turbines or other steam consuming units, it is necessary for a balanced operation that feedwater be returned to each of the banks of boilers in proportion to the amount of steam supplied thereby. The term "bank of boilers" as used herein includes one or more boilers connected in parallel to a common load and having a common feedwater return system. Otherwise, feedwater may be dumped at one bank and make-up water added at the other resulting in a loss in efficiency. It is the principal object of the present invention to provide a control system which will accomplish this result.

Another object is to provide a control system in which separate feedwater pumps receiving condensate from separate condensers connected to the separate steam consuming devices are controlled in response to the ratio of steam flow to feedwater flow from one bank of boilers to the other.

A further object is to provide a control system in which the control is corrected in response to an excess or deficiency of feedwater at one of the return pumps.

The above and other objects and advantages of the invention will be more readily apparent from the following description when read in connection with the accompanying drawing in which the single figure is a diagrammatic illustration of a control system embodying the invention.

In the system illustrated, there are two banks of boilers each of which contains two individual boilers, although it will be apparent that a single boiler or more than two boilers might be contained in each bank. As shown, one bank contains boilers 10 and 11 and the other bank contains boilers 12 and 13. The boilers 10 and 11 supply steam through outlet pipes 14 and 15 to a header 16 which is connected at one end to a steam turbine 17. The boilers 12 and 13 supply steam through outlet conduits 18 and 19 to the same header 16 which is connected at its opposite end to a turbine 21. With this connection, it will be apparent that the turbine 17 is principally supplied by the boilers 10 and 11 and that the turbine 21 is principally supplied by the

2

boilers 12 and 13. However, it is possible for steam to flow through the header 16 from one bank of boilers to the other.

In one type of installation, the boilers 10 and 11, for example, might be older boilers, while boilers 12 and 13 might be newer, more efficient boilers. It is, therefore, desirable in such an installation to run the boilers 12 and 13 at full capacity to supply all of the steam for the turbine 21 and a part of the steam for turbine 17 and to run the boilers 10 and 11 only during peak load periods. Other installations of this same general type may be found and may be desirable to meet particular conditions, and the installation as described is intended to be only one example of such a system.

Steam discharged from the turbine 17 is condensed in a condenser 22 and is pumped by a pump 23 into a deaerator tank 24. The deaerator tank 24 contains a float 25 controlling a bypass valve 26 to dump excess condensate when the level in the deaerator tank becomes excessive. From the deaerator tank boiler feedwater flows through heater 27 to a pair of feedwater pumps 28 connected in parallel and driven by turbines 29. The discharge from the feedwater pumps 28 goes through a heater 31 into a feedwater return manifold 32 which is connected to all four of the boilers 10, 11, 12 and 13. Each boiler may be provided with an individual feedwater control indicated at 100 to control supply of feedwater thereto from the header 32 to maintain the proper level therein.

Steam discharged from the turbine 21 is condensed in a condenser 33 and is pumped by a pump 34 into a deaerator tank 35. The tank 35 contains a float 36 controlling a bypass valve 37 similar to the valve 26. From the deaerator feedwater flows to a surge tank 38 and through heaters 39 to feedwater pumps 41 connected in parallel. The pumps 41 are driven by turbines 42 and the discharge from said pump moves through a heater 43 into the feedwater return manifold 32.

With this system the feedwater pumps 28 pump into the header 32 a quantity of condensate proportional to the steam condensed in the condenser 22 and the pumps 41 pump a quantity proportional to the steam condensed in condenser 33. If the turbine 17 and condenser 22 are drawing steam from boilers 12 and 13 the pumps 28 will return more condensate than is required by the boilers 10 and 11 to maintain proper water flow-steam flow balance and the pumps 41 will return a correspondingly lesser

amount than is required by the boilers 12 and 13. The excess condensate pumped by the pumps 28 will therefore, flow from left to right in the header 32 into the boilers 12 and 13. The present invention provides a control system for the feedwater pumps to maintain a proper steam flow-water flow balance in the several boilers.

When the amount of steam flowing from one bank of boilers toward the other through the header 16 is proportional to the amount of water flowing from the other bank toward the one bank through the header 32 the system is in balance.

The flow through the feed water pumps 28 is controlled by regulators 44 which are responsive to loading pressure supplied through lines 45 and to the flow through the respective pumps as measured by the drop across orifices 46. The regulators 44, as well as some of the other regulators to be referred to hereinafter, may be of the type more particularly described in Smoot Reissue Patent No. 16,507 or in O'Connor 2,039,924 or may be transmitters of the type shown in the patent to Rosenberger, No. 2,431,200. The regulators control valves 47 which in turn control the supply of steam to the turbines 29 to control the pump.

As shown each regulator 44 includes a balance beam 81 urged in one direction by a diaphragm 82 whose opposite sides are connected to opposite sides of the restriction 46. A loading diaphragm 83 responsive to the loading pressure in line 45 opposes the diaphragm 82 to modify the force exerted thereby in response to flow.

The beam 81 controls a bleed nozzle 84 supplied with air past a restriction 85 to produce a regulated pressure. The nozzle 84 is connected to a diaphragm 86 which urges the beam in the other direction to balance it and to the control valve 47 to control it.

The pumps 41 are similarly controlled by regulators 48 supplied with loading pressure through lines 49 and responsive to the flow through the associated pumps as measured across orifices 51. The regulators 48 control valves 50 which control the supply of steam to the turbines 42. The several loading pressures to the lines 45 and 49 are supplied thereto through transfer units 52, all of which may be identical. Each of the transfer units 52 may contain switch-over valves to supply automatically regulated loading pressure to the lines or to supply manually adjusted loading pressure for manual operation of the system, and may further contain ratio control valves to vary the loading pressures as desired. Since these units are purely conventional units whose construction forms no part of the present invention, they are not illustrated in detail.

The automatic loading pressure to control the regulators 48 is supplied to the corresponding transfer units 52 through a pipe 53 leading from a relay valve 54 in a regulator 55 which may be of the type shown in the patent to O'Connor No. 2,039,924. The relay valve as shown may be of conventional construction including a diaphragm 154 dividing a hollow casing 155 and carrying a central valve pin 156 controlling a vent opening in the bottom of the casing. The lower part of the casing is supplied with pressure from a regulator 67 described hereinafter and is also connected through the transfer units 52 to the regulators 48. A spring 157 urges the diaphragm down and seats against a movable block connected to the beam 56.

When the block is moved downward by the beam 156 the pressure below the diaphragm will

increase to a valve closer to that supplied from the regulator 67 and when the block moves up the pressure will decrease. The regulator 55 is jointly responsive to steam flow and condensate flow through the headers in a direction from one bank of boilers to the other and may be corrected in response to an excess or deficiency of condensate in one of the deaerator tanks. As shown, the regulator includes a balanced beam 56 pivoted intermediate its ends and urged in one direction by a diaphragm 57 which is supplied with loading pressure by a flowmeter or transmitter 58 responsive to the differential across an orifice 59 in the steam header 16 between the banks of boilers. The flowmeter or transmitter may be of the type disclosed in the patent to Rosenberger, No. 2,220,176. A second flowmeter or transmitter 61 responsive to the differential across an orifice 62 in the feedwater return header 32 between the banks of boilers supplies a loading pressure to a diaphragm 63 which opposes the diaphragm 57. In normal operation, as long as the steam flow and feedwater flow between the banks of boilers is in the correct proportion, the beam 56 will be balanced and the relay valve 54 will be kept in its normal position to transmit a loading pressure through the transfer units 52 to the regulators 48.

In the event that an excessive amount of condensate should accumulate in one of the deaerator tanks it is necessary to make a correction to prevent dumping of condensate. For this purpose a transmitter 64 is provided responsive to the condensate level in the deaerator tank 24. The transmitter 64 is a conventional instrument as shown for example in the patent to Rosenberger, No. 2,431,200, and supplies loading pressure to a correcting diaphragm 65 acting on the weigh beam 56 which is pivoted intermediate its ends and opposing the diaphragm 63. The transmitter 64 as shown includes a balance beam 87 urged in one direction by a diaphragm 88 connected to the lower part of the tank 24 to exert a force proportional to the water level in the tank. The beam is urged in the opposite direction by a diaphragm 89 connected to a bleed nozzle 91 which is supplied with air through a restriction 92. The nozzle is also connected to the diaphragm 65 to supply loading pressure thereto. When the level in the tank 24 is within the desired limits, the transmitter 64 will send out a steady loading pressure of a normal value. If the level in the tank 24 should increase above the desirable limits, the loading pressure sent out by the transmitter 64 will increase to increase the effect of the diaphragm 65. This reduces the effective force of the diaphragm 63 tending to move the block 157 up to decrease the pressure supplied to the transfer units 52 and regulators 48 and has the same result as an insufficient flow of feedwater from left to right in the header 32. As explained more fully hereinafter, this will reduce the speed of the pumps 41 and increase the speed of the pumps 28 to pump more water from the tank 24 so that the level therein will be reduced. Simultaneously less water will be pumped from tank 35 so that the level therein which will be too low under the conditions stated, will increase. Similarly, should the level fall too low in the tank 24, the loading pressure on diaphragm 65 will be decreased to increase the effect of the diaphragm 63 and increase the speed of pumps 41 while decreasing the speed of pumps 28. In this way the level in the tank 24, which is a measure of the difference between the quan-

tity of condensate delivered by the condenser 22 and pumped by the pumps 28, serves to correct the system to prevent an unbalanced condition therein.

The pressure to the relay valve 54, which is modified by operation of the regulator 55, is in effect a master loading pressure supplied through a pipe 66 from a regulator 67. The regulator 67 contains a relay valve 68 supplied with air from a suitable source past a restriction 69 and sending out a master loading pressure into the pipe 66 in accordance with the operation of the regulator. The regulator 67 is controlled in response to a function of the feedwater return in the header 32. As shown, a pipe 71 connects the header 32 to a diaphragm 93 in the regulator 67 so that the regulator is responsive to the pressure in the header. The diaphragm 93 urges a balance beam 94 in one direction and the beam controls the valve or nozzle 68 to produce the master loading pressure. The beam is balanced by a diaphragm 95 which is connected to the valve or nozzle 68 to be responsive to the loading pressure. In operation, the regulator tends to control the other regulators in the system in a manner to maintain the header pressure constant so that an adequate supply of feedwater will be available for all of the boilers.

The loading pressure for the regulators 44 is supplied by a flow balance relay which functions to maintain the total flow through all of the feedwater pumps at the proper value and to proportion the flows through the separate pumps 28 and 41 so that the proper amount of condensate will be pumped by each. The flow balance relay as shown includes a balance lever 72 urged in one direction by a diaphragm 73 connected to the pipe 66 to be responsive to the master loading pressure. The lever is urged in the opposite direction by a pair of diaphragms 74 and 75 which act in parallel so that their total force must be such as to balance force of the diaphragm 73. As shown, the diaphragm 74 is connected to the pipe 53 to be responsive to the master loading pressure supplied to the regulators 48.

A nozzle 76 is mounted adjacent the lever 72 and is supplied with air through a restricted orifice 77 so that the pressure back of the nozzle will be a regulated loading pressure controlled by balance of the relay lever 72. This regulated loading pressure is supplied through a pipe 78 to the diaphragm 75 and through the left hand transfer units 52 to the regulators 44.

In operation, assuming that steam is flowing from the bank of boilers 12 and 13 to the turbine 17 and that feedwater is flowing from left to right through the header 32, if the steam flow from boilers 12 and 13 and feedwater flow to boilers 12 and 13 is in balance, both banks of boilers will receive an amount of feedwater directly proportional to the amount of steam supplied thereby and the several feedwater pumps will be pumping the proper quantity of feedwater. In the event more than two banks of boilers are employed each bank will be equipped with the individual controls shown and the controls responsive to flows through the headers will be provided in the headers between each bank and the adjacent banks.

If the pumps 28 should be pumping insufficient feedwater into the header 32 to maintain the desired balance, the flow through header 32 past the orifice 62 will be too small and the loading pressure supplied to diaphragm 68 will be too

low properly to balance the beam 56. Under these conditions, the relay valve 54 will be adjusted to reduce the loading pressure supplied to the regulators 48 and these regulators will reduce the speed of the feedwater pumps 41. At the same time, the pressure on diaphragm 74 is reduced so that the lever 72 will rock clockwise to approach the nozzle 76. This will increase the loading pressure in line 78 to the point where the diaphragm 75 will re-balance the lever 72, and at the same time, will increase the loading pressure acting on the regulators 44. These regulators will open the valves 47, increasing the supply of steam to the turbines 29 and increasing the quantity of feedwater pumped by the pumps 28. If the system is properly adjusted, the increase in the amount pumped by the pumps 28 and the decrease in the amount pumped by the pumps 41 will be equal and will be sufficient to restore the proper steam flow and feedwater flow balance. In the event the pumps 28 are pumping too much so that the flow past the orifice 62 is too great for proper balance, the operation will be the reverse of that described.

If the system should get out of adjustment or should not be perfectly adjusted, the level of condensate in the tank 24 will tend either to increase or decrease beyond the desired values. Under these conditions, the transmitter 64 will operate the diaphragm 65 to adjust the regulator 55 so that proper balance in the flows is restored. It will thus be seen that with the present system feedwater return balance is maintained under all conditions so that there is no unnecessary dumping of condensate.

While one embodiment of the invention has been illustrated and described in detail, it will be apparent that many changes might be made therein and the embodiment shown is for the purpose of illustration only and is not to be taken as a definition of the scope of the invention, reference being had for this purpose to the appended claims.

What is claimed is:

1. A feedwater control system for a power plant including a plurality of banks of steam boilers interconnected by steam and feedwater headers for flow of steam and feedwater between said banks, a condenser for each bank of boilers adapted to be connected to a steam consuming unit to receive steam therefrom, and a feedwater pump connecting each condenser to its associated set of boilers, said control system comprising control means for each feedwater pump, a flowmeter connected to the steam header for measuring flow of steam through the steam header from one bank of boilers to the other, a flowmeter connected to the feedwater header for measuring the flow of water through the feedwater header from one bank of boilers to the other, a balance control device connected to the control means to maintain a predetermined flow balance through the feedwater pumps, and means jointly responsive to the flowmeters acting on the balance control device to vary said flow balance.

2. A feedwater control system for a power plant including a plurality of banks of steam boilers interconnected for flow of steam and feedwater therebetween, a condenser for each bank of boilers adapted to be connected to a steam consuming unit to receive steam therefrom, and a feedwater pump connecting each condenser to its associated set of boilers, said control system comprising control means for each feedwater pump, a flowmeter for measuring flow of steam

through the steam header from one bank of boilers to the other, a flowmeter connected to the feedwater header for measuring flow of water through the feedwater header from one bank of boilers to the other, a balance control device connected to the control means to maintain a predetermined flow balance through the feedwater pumps, means jointly responsive to the flowmeters acting on the balance control device to vary said flow balance, and means responsive to the quantity of condensate delivered by one of said condensers to vary the effect of the last named means.

3. A feedwater control system for a power plant including a plurality of banks of steam boilers interconnected by steam and feedwater headers for flow of steam and feedwater between said banks, a condenser for each bank of boilers adapted to be connected to a steam consuming unit to receive steam therefrom, and a feedwater pump connecting each condenser to its associated set of boilers, said control system comprising control devices of each feedwater pump, a flow meter connected to the steam header for measuring the flow of steam through the steam header from one bank of boilers to the other, a flow meter connected to the feedwater header for measuring the flow of feedwater through the feedwater header from one bank of boilers to the other, a regulator jointly responsive to the flow meters to control one of the control devices, and a flow balance relay responsive to the regulator to control another of the control devices in a direction inverse to the direction of control of said one of the control devices.

4. A feedwater control system for a power plant including a plurality of banks of steam boilers interconnected for flow of steam and feedwater therebetween, a condenser for each bank of boilers adapted to be connected to a steam consuming unit to receive the steam therefrom, and a feedwater pump connecting each condenser to its associated set of boilers, said control system comprising control devices for each feedwater pump, a flowmeter for measuring the flow of steam through the steam header from one bank of boilers to the other, a flowmeter connected to the feedwater header for measuring the flow of feedwater through the feedwater header from one bank of boilers to the other, means responsive to the quantity of condensate delivered by one of the condensers, a regulator jointly responsive to the last named means and to one of the flowmeters to control one of the control devices, and a flow balance relay responsive to the regulator to control another of the control devices inversely to said control of said one of the control devices.

5. A feedwater control system for a power plant including a plurality of banks of steam boilers interconnected for flow of steam and feedwater therebetween, a condenser for each bank of boilers adapted to be connected to a steam consuming unit to receive steam therefrom, and a feedwater pump connecting each condenser to its associated set of boilers, said control system comprising control devices for each feedwater pump, a flowmeter for measuring the flow of steam through the steam header from one bank of boilers to the other, a flowmeter connected to the feedwater header for measuring the flow of feedwater through the feedwater header from one bank of boilers to the other, a regulator responsive to the pressure of the feedwater simultaneously to control both of the control devices, a regulator jointly responsive to the flowmeters to modify the

control of one of the control devices by the first named regulator, and a flow balance relay responsive to the last named regulator which is jointly responsive to the flowmeters to modify the control of another of the control devices by the first named regulator.

6. A feedwater control system for a power plant including a plurality of banks of steam boilers interconnected for flow of steam and feedwater therebetween, a condenser for each bank of boilers adapted to be connected to a steam consuming unit to receive steam therefrom, and a feedwater pump connecting each condenser to its associated set of boilers, said control system comprising a pair of control devices for the feedwater pumps respectively, a flowmeter for measuring the flow of steam through the steam header from one bank of boilers to the other, a flowmeter connected to the feedwater header for measuring the flow of feedwater through the feedwater header from one bank of boilers to the other, a regulator responsive to the pressure of the feedwater simultaneously to control both of the control devices, means responsive to the quantity of condensate delivered by one of the condensers, a second regulator jointly responsive to the flowmeters and the last named means to modify the control of one of the control devices by the first named regulator, and a flow balance relay responsive to the second regulator to modify control of the other of the control devices by the first named regulator.

7. A feedwater control system for a power plant including a plurality of banks of steam boilers interconnected by steam and feedwater headers for flow of steam and feedwater between said banks, a condenser for each bank of boilers adapted to be connected to a steam consuming unit to receive steam therefrom, and a feedwater pump connecting each condenser to its associated set of boilers, said control system comprising a control device for each of the feedwater pumps, flowmeters connected to the headers and responsive respectively to steam flow and feedwater flow through the headers from one bank of boilers to the other to develop loading pressures proportional to functions of the flows, a flow balance relay including means to produce a force in one direction and a pair of units to produce balancing forces in the opposite direction, a regulator jointly responsive to the flowmeters to regulate a loading force acting on one of the units and controlling one of the devices, and means responsive to unbalance of the relay to produce a second loading force acting on the other unit and controlling the other control device.

8. A feedwater control system for a power plant including a plurality of banks of steam boilers interconnected by steam and feedwater headers for flow of steam and feedwater between said banks, a condenser for each bank of boilers adapted to be connected to a steam consuming unit to receive steam therefrom, and a feedwater pump connecting each condenser to its associated set of boilers, said control system comprising a control device for each of the feedwater pumps, flowmeters connected to the headers and responsive respectively to steam flow and feedwater flow through the headers from one bank of boilers to the other to develop loading pressures proportional to functions of the flows, a flow balance relay including means to produce a force in one direction and a pair of units to produce balancing forces in the opposite direction, means responsive to the difference between the quantity of con-

densate discharged by one of the condensers and the quantity pumped by the connected pump, a regulator jointly responsive to the flowmeters and the last named means to regulate a loading force acting on one of the units and controlling one of the control devices, and means responsive to unbalance of the relay to produce a second loading force acting on the other unit and the other of the control devices.

9. A feedwater control system for a power plant including a plurality of banks of steam boilers interconnected by steam and feedwater headers for flow of steam and feedwater between said banks, a condenser for each bank of boilers adapted to be connected to a steam consuming unit to receive steam therefrom, and a feedwater pump connecting each condenser to its associated set of boilers, said control system comprising a control device for each of the feedwater pumps, flowmeters connected to the headers and responsive respectively to steam flow and feedwater flow through the headers from one bank of boilers to the other to produce loading pressures proportional to functions of the flows, a flow balance relay including a first pressure responsive unit to produce a force in one direction and second and third pressure responsive units to produce balancing forces in the opposite direction, a regulator responsive to the pressure of the feedwater to produce a loading pressure acting on the first unit, a regulator jointly responsive to the flowmeters and receiving loading pressure from the first regulator to modify the loading pressure and supply the modified pressure to the second unit and one of the control devices, and means responsive to unbalance of the relay to produce a loading pressure acting on the third unit and the other of the control devices.

10. A feedwater control system for a power plant including a plurality of banks of steam boilers interconnected by steam and feedwater headers for flow of steam and feedwater between said banks, a condenser for each bank of boilers adapted to be connected to a steam consuming unit to receive steam therefrom, and a feedwater pump connecting each condenser to its associated set of boilers, said control system comprising a control device for each of the feedwater pumps, flowmeters connected to the headers and responsive respectively to steam flow and feedwater flow through the headers from one bank of boilers to the other to produce loading pressures proportional to functions of the flows, a flow balance relay including a first pressure responsive unit to produce a force in one direction and second and third pressure responsive units to produce balancing forces in the opposite direction, a regulator responsive to the pressure of the feedwater

of the feedwater to produce a loading pressure acting on the first unit, means responsive to the difference between the quantity of condensate delivered by one of the condensers and the quantity pumped by the connected pump, a regulator jointly responsive to the flowmeters and the last named means and receiving loading pressure from the first regulator to modify the loading pressure and supply the modified pressure to the

5 second unit and one of the control devices, and means responsive to unbalance of the relay to produce a loading pressure acting on the third unit and the other of the control devices.

10 11. A feedwater control system for a power plant including a plurality of banks of steam boilers, steam and water headers connected to all of the boilers, and a plurality of feedwater pumps connected to spaced points on the feedwater header, said control system comprising

15 control means for each feedwater pump, a flowmeter in the steam header to measure the flow of steam through the steam header from the point of connection of one bank of boilers thereto to the point of connection of the other bank of boilers thereto, a flow meter in the water header to measure the flow of water therethrough between said spaced points thereon, a balance control device connected to the control means to maintain a predetermined flow balance through the 20 feedwater pumps, and means jointly responsive to the flowmeters acting on the balance control device to vary said flow balance.

25 12. A feedwater control system for a power plant including a plurality of banks of steam boilers, steam and water headers connected to all of the boilers, a plurality of condensers, and a feedwater pump connecting each of the condensers to the water header, said control system comprising

30 a control device for each of the feedwater pumps, control means responsive to the quantity of condensate delivered by one of the condensers to produce a controlling force, means responsive to said controlling force to control the control device for one of the feedwater pumps, and a 35 relay responsive to said last named means to control the control device for another of the feedwater pumps inversely to the control of the first named control device.
